UNITED STATES PATENT OFFICE

2,000,957

COMBINATION TELEPHONE STAND AND
TELEPHONE DIRECTORY SECRETARY

John G. Hunter, Columbus, Ohio

Application November 1, 1932, Serial No. 640,716

7 Claims. (Cl. 45—6)

My invention comprises new and useful improvements in desks and stands adapted especially for telephone users whereby a simple, inexpensive and convenient means is provided for holding a telephone directory and a telephone in a convenient position for use, the structure being such that it will serve as a desk when in the open position and as a container for the telephone directory when closed, there being a hinged leaf that supports a memorandum telephone directory and memorandum pad, which, when the door of the cabinet is in the open position, will assume a convenient position for supporting the pad or tablet for writing thereon, and which is automatically folded in to permit the container to assume the closed position.

Further, it is an object of the invention to provide an improved structure having the above characteristics in which there is a casing having a drop door hinged thereto and provided with braces to hold it horizontally as a desk, a shelf being rigidly mounted in the casing and supporting a paper rack and itself having a grooved portion constituting a pen and pencil rack; a leaf which is adapted to carry a memorandum pad and a small directory in which telephone numbers frequently called may be kept, is hingedly carried by the hinged door adjacent its hinge, the shelf carrying a device that cooperates with the leaf to hold it in useful position when the hinged door is open and to deflect the leaf away from the paper rack as the door is closed, the movement of the leaf being under the combined influence of gravity and that of the moving door.

Further, it is an object to provide a secretary of the kind indicated of such construction that a telephone instrument may be located within the casing or be located on top of the casing outside thereof at will, there being an illuminating means in the top of the casing so designed and constructed as to illuminate the telephone instrument both when it is located within the casing and when it is disposed outside and on top of the casing.

Further, it is an object to provide a secretary having the above mentioned characteristics and in addition thereto being so constructed that when the casing is closed no light rays will escape from the cabinet or be visible from the outside thereof.

Again, it is an object to provide a new and improved simplified means to hold the telephone directory to the inner face of the hinged door without its interfering with the hinged leaf and its carried articles during the opening and closing

of the door and in a manner to enable the free and unobstructed turning of the leaves of the book when in use.

Further, the invention seeks to improve the secretary which constitutes the invention of my Patent No. 1,969,305, dated August 7, 1934, particularly in the elimination of the externally disposed reflector 29 therein disclosed as well as in other features of construction which will be apparent on comparison of the drawings of this application with those of the application aforesaid.

Other objects will in part be obvious and in part be pointed out hereinafter.

To the attainment of the aforesaid objects and ends, the invention still further resides in the novel details of construction, combination and arrangement of parts all of which will be first fully described in the following detailed description, then be particularly pointed out in the appended claims, reference being had to the accompanying drawings, in which:

Figure 1 is a front elevation of my improved secretary closed.

Figure 2 is a side elevation of the same.

Figure 3 is a detail vertical section on the line 3—3 of Figure 1 with the doors open.

Figure 4 is a detail vertical section on the line 4—4 of Figure 3.

Figure 5 is a plan of the top of the cabinet with the top door open.

Figure 6 is a vertical cross section showing a modification of the invention.

In the drawings in which like numerals of reference designate like parts in all of the figures, it will be seen that the secretary comprises a body which is preferably supported at a suitable height by standards 1 having feet 48, the standards being suitably cross-braced at 42. The upper extremities of the standards 1 may constitute the sides 3 of the cabinet body, the body being composed of the bottom 2, sides 3, back wall 5, top 4—7—4, and front 12—13—23.

The front of the cabinet body is composed of a fixed front panel 13 and a hinged closure or door 23, the closure being hinged along the lower edge to the bottom 2 as at 24. The closure 23 also has a flange 26 on three sides, the top flange having an extension 27 for a purpose presently explained.

The top of the cabinet is composed of two fixed panels 4—4 spaced apart and a top door 7 between these panels, hinged at 8 to the back wall 5. The opposite edges of the panels 4—4 are stepped as at 6 to receive the side flanges 9 of the door 7 when it is closed to prevent light from

within the cabinet passing through the joint. The top faces of the panels 4—4 and that of the top door 7 lie flush when the door is closed.

When opened, the door 7 is held up by resting 5 against a suitable stop 10, there being a knob 11 provided on the door, by means of which it may be raised and lowered.

A molding 12 is fitted around the front and two sides of the cabinet in the plane of the top 10 and adds to the ornamental appearance of the secretary, as well as serving to prevent the escape of light rays under the front edge of the door 7 when it is closed.

Beneath the door 7 and below the plane of the 15 top is secured a metal plate 17. This plate is made fast to the back wall 5 and has its front edge resting on a ledge 14 in the rear or inner face of the front panel 13, thus forming the bottom of a well in which and on the plate 17 a telephone set may be placed when the door 7 is in the opened position.

The front panel 13 has a recess 15 in its front edge to cooperate with a similar recess 28 in the door 23 for passing the telephone cord 44 of the 25 telephone set 43 when it is desired to rest the set in the top well instead of leaving it in the cabinet.

The electric circuit of the light bulb 18 may be controlled by a suitable switch set into the back 30 of the front panel 13 with the button 16 thereof passed through to the front outside of the panel. The bulb 18 is supported on a suitable bracket 19 and is wholly located within the top part of the cabinet beneath the plate 17.

At each side of the plate 17 and spaced therefrom, suitable reflectors 20 are mounted in the cabinet, and the under surfaces of the top panels 4 from the reflectors 20 to the stepped edge 6 are inclined upwardly to provide light passes 22 around and over the side edges of the plate 17 40 to a telephone standing in the well on the plate thereby to illuminate the dial.

The closure 23 has a knob 25 by the use of which the closure may be moved to the open and closed positions.

45 The flange extension 27 of the closure 23 serves to overlie the recesses 15—28 when the door is closed to prevent light rays being visible from the outside of the cabinet.

Suitable articulated braces 29, hinged at 30 to 50 the side walls 3 and at 31 to the door 23, serve to hold the door horizontal as a desk when fully opened.

Adjacent the hinged edge of the door or closure 23 is a cleat 32 that is fixed to the door in any 55 suitable way. This cleat performs a two-fold function, namely it serves as a back stop for the telephone directory 49, which is held to the door at its front edge by a U-shaped spring clip 33 that clips over the directory and has one leg located in a bore or hole 34 in the door. The other function of the cleat is to support a hinged leaf.

Rigidly secured to the back wall 5 of the cabinet and at a suitable height above the bottom 2 is a shelf 35 having pen and pencil rack grooves 36 65 and sustaining a paper rack 37.

Secured to and projecting forwardly from the shelf 35 is a leaf deflector and rest 40 on which the upper free edge of a leaf 38 lies. The lower edge of the leaf 38 is hinged at 39 to the cleat 32. 70 The shelf 35, leaf 38, rack 37 and cleat 32 are so designed and correlated that on opening and closing the door 23 the free end of the leaf 38 will not strike against or engage the rack 37 but will be deflected upwardly and away from the 75 rack.

The back wall 5 has a hole 41 to pass the telephone cord 44 and the telephone 43 may be contained within the cabinet, resting on the bottom 2, or it may be placed in the well in the top of the cabinet when the top door 7 is open, as may be found most convenient.

A calendar 45 may be mounted in any suitable way on the front wall of the rack 37 and a memorandum telephone directory 46 and a memorandum pad 47 may be suitably mounted 10 on the leaf 38.

It will be seen that the height of the cleat 32 is less than the distance from the door 23 to the shelf 35 so that when the door is closed the leaf 38 will still incline rearwardly and will not 15 fall forward and interfere with the telephone book 49.

If found desirable the plate 17 may have an opening or openings 51 in the front, and a front reflector 50 may be provided to reflect light rays 20 over the telephone dial from the front as well as from the sides, see Figure 6.

Other modifications of the details of structure may be made by those skilled in the art without departing from the spirit of the invention or the 25 scope of the appended claims.

In this application I make no claim to the desk supported telephone and means for illuminating the telephone dial as that constitutes the subject matter of a divisional application filed Aug. 9, 30 1934, Ser. No. 739,141.

From the foregoing description, taken in connection with the accompanying drawings it is thought the complete construction, operation and advantages of my invention will be clear to those 35 skilled in the art to which it relates.

What I claim is:

1. A secretary having a chambered body provided with a door hingedly connected at its bottom edge to the body, a brace to hold the door 40 when opened in an approximately horizontal plane, a leaf hingedly mounted at its lower edge on the door and a baffle stop located within the body by which the leaf is deflected upwardly and away from the back of the body as the door is 45 closed.

2. A secretary having a chambered body provided with a door hingedly connected at its bottom edge to the body, a brace engaging the door and body to hold the door when opened in an 50 approximately horizontal plane, a shelf within the body, a leaf hingedly mounted at its lower edge on the door and a baffle stop located on the shelf against which stop the upper edge of the leaf lies and by which it is deflected upwardly 55 and away from the shelf as the door is closed.

3. A secretary having a chambered body provided with a door hingedly connected at its bottom edge to the body, a brace engaging the door and body to hold the door when opened in an 60 approximately horizontal plane, a support secured to the door a leaf hingedly mounted at its lower edge on the support and a baffle stop located within the body against which stop the upper edge of the leaf lies and by which it is deflected upwardly and away from the back of the body as the door is closed, the support comprising a back stop for a telephone directory laid 65 on the open door.

4. A secretary having a chambered body provided with a door hingedly connected at its bottom edge to the body, means to hold the door when opened in an approximately horizontal plane, a member secured to the door a leaf hingedly mounted at its lower edge on the member 70

- and a baffle stop located within the body against which stop the upper edge of the leaf lies and by which it is deflected upwardly and away from the back of the body as the door is closed, a 5 U-shaped spring clip fitted into the door and over the leaves of the directory, said member performing the dual function of cooperating with said door as an actuating lever for moving said leaf and also cooperating with said U-shaped 10 clip to hold the directory to the door.
5. A secretary having a chambered body provided with a door hingedly connected at its bottom edge to the body, a brace engaging the door and body to hold the door when opened in an 15 approximately horizontal plane, a shelf within the body, a leaf hingedly mounted at its lower edge on the door and a baffle stop located on the shelf against which stop the upper edge of the leaf lies and by which it is deflected upwardly 20 and away from the shelf as the door is closed, a paper rack mounted on said shelf adjacent the back thereof, leaving the front of the shelf projecting forward beyond the rack, the location of said rack and said shelf being such that said leaf 25 will pass up in front of it and clear the same when the door is closed.
6. A secretary having a chambered body provided with a door hingedly connected at its bottom edge to the body, means to hold the door
- when opened in an approximately horizontal plane, a shelf within the body, a cleat secured to the door a leaf hingedly mounted at its lower edge on the cleat and a baffle stop located on the shelf against which stop the upper edge of the leaf lies and by which it is deflected upwardly and away from the shelf as the door is closed, a U-shaped spring clip fitted into the door and over the leaves of the directory, said cleat performing the dual function of cooperating with 10 said door as an actuating lever for moving said leaf and cooperating with said U-shaped clip to hold the directory to the door, a paper rack mounted on said shelf adjacent the back thereof, leaving the front of the shelf projecting forward 15 beyond the rack, the location of said rack and said shelf being such that said leaf will pass up in front of it and clear the same when the door is closed. 20
7. In a secretary having a chambered body provided with a closure adapted to open horizontally as a desk, means to hold a telephone directory on said closure, said means having a member secured to said closure adjacent one edge forming a back stop for the telephone directory and a U-shaped clip inserted into a hole in the opposite edge of the closure and over the leaves of the directory to hold it to the closure. 25

JOHN G. HUNTER.
